UNITED STATES PATENT OFFICE

MARTIN A. PAULSON, OF RICE LAKE, WISCONSIN, ASSIGNOR TO NEW IDEA POTATO MACHINERY CO., OF RICE LAKE, WISCONSIN, A CORPORATION OF WISCONSIN

POTATO AND ONION GRADER

Application filed October 14, 1929. Serial No. 399,510.

This invention relates to a vegetable grader and particularly to the sorting or grading belt used in such graders. A common type of vegetable grader is now used which comprises a trough having an open bottom and through which travels an open-work belt. The vegetables are fed to this belt and those of a certain size will drop through the belt as it progresses through the trough and those 5 of a larger size will be retained on the belt. In such a grader it is desirable to have a trough which is simple in construction so that it can be easily and inexpensively made, one which is durable and which has an efficient 10 action in the machine. It is also desirable to have a belt the side portions of which move closely adjacent the side portions of the trough so that there is no danger of vegetables or foreign matter collecting or getting caught 15 between the edges of the belt and the sides of the trough.

It is an object of this invention, therefore, to provide a sorting belt of simple and efficient construction, one which is flexible and 20 durable and which has side portions extending substantially in straight lines respectively so as to move close to the sides of the trough in which it is disposed.

It is a further object of the invention to 25 provide a sorting belt comprising a plurality of wires or rods bent into zigzag form slightly out of one plane, the same being woven together to form a belt having diamond shaped openings arranged in staggered relation, the end portions of said members being 30 bent to extend substantially perpendicular to the general directions of said members and being connected together by inter-engaging 35 loops or eyes.

It is another object of the invention to provide such a belt as above set forth which also 40 comprises an end member bent into zigzag form having its angle portions at one side engaging with the adjacent member of the belt and having the angle portions at its other side formed with bights bent into the 45 form of hooks, the end portion of this end member being also bent substantially perpendicular to its length and pivotally con-

nected to the end portions of the adjacent member on said belt.

These and other objects and advantages of the invention will be fully set forth in the following description made in connection with the accompanying drawing, in which like reference characters refer to similar parts throughout the several views, and in which:—

Fig. 1 is a perspective view of a machine 55 in which the belt is used;

Fig. 2 is a plan view of the belt shown on an enlarged scale;

Fig. 3 is a view partly broken away showing the edge of the belt or screen only;

Fig. 4 is an edge view of a portion of the 60 end member of the belt.

Referring to the drawing, in Fig. 1 a vegetable sorting machine is shown comprising a hopper 10, an upwardly extending trough 11 leading from the hopper which has a discharge chute 12. Rollers 13 and 14 are disposed adjacent the ends of trough 11 having trunnions journaled in bearings at the sides of the trough and an endless belt 15 of open-work formation runs over rollers 13 and 14, said belt passing downward below the trough 70 in its return movement. A discharge chute 16 is shown below the trough and a bag 17 is shown in position to receive from the discharge chute 12. The belt will be driven by turning the roller 14, which may be turned by any suitable means, a crank 18 being shown as attached to the trunnion of roller 14 for this purpose. The parts of the machine are supported upon a suitable frame 75 including the four legs 19 disposed at the corners of a rectangle.

In accordance with the present invention, a belt is used which is shown in Fig. 2 and 80 which comprises a plurality of members 15a in the form of wires or rods, the same being bent into zigzag form. While the angle between the successive bends of these members 85 may be varied, in the embodiment of the invention the angle is shown as approximately 60 degrees. The portions of the members 15a will be bent slightly out of one plane so that the same may be inter-twined with adjacent members as shown in Fig. 2 to form 95 100

a continuous belt. It will be seen that this belt will be quite flexible at the points where the angle portions of the members intertwine. The end portions 15b of members 15a are bent toward each other in alternate pairs of adjacent members and extend in a direction substantially perpendicular to the general direction of the members. These end portions 15b are provided with loops or eyelets 15c which are inter-engaged to pivotally connect said end members. These loops 15c are in transverse alignment with the inter-engaging portions or angles of said members 15a. It will thus be seen that the members 15a can swing about transverse axes extending through the centers of the eyelets 15c and substantially through the bight portions or angular portions of said members.

An end member 15d is provided for the belt 20 which member also is made of a wire or rod bent into zigzag form, the angles at one side of said member being the same as the angles for the members 15a and inter-twined with the angle portions of the adjacent member 25 15a. The other and outer angle portions of member 15b are formed with bights 15e the sides of which are substantially parallel said bight portions being bent toward the adjacent member 15a to form hooks 15f as shown 30 in Figs. 2 and 4.

In operation the belt 15 will move over the rollers 13 and 14 and through the trough 11. The sides of the belt formed by the portions 35 15b can move close to and parallel to the sides of trough 11 so that no vegetables or any foreign matter of any appreciable size can get in between the sides of the trough and the sides of the belt. Furthermore, the sides of the belt substantially engage the sides of 40 the trough so that the belt is accurately guided and lateral vibration thereof is prevented. At the same time the belt is quite flexible and the flexibility of the belt is not hampered by the connections of the members at the sides 45 of the belt. It will be seen that a new member 15a can readily be inserted in the belt at any point by opening the eyes 15c and then threading the member into engagement with adjacent members and moving it transversely 50 of the belt. The zigzag portions of the members 15a which surround the diamond shaped openings act effectively to hold a vegetable in said opening. The vegetable seats nicely in the opening which has somewhat of 55 a dished formation. The end member 15d is quite handy as the other end of the belt can be readily connected to the hooks 15f and an endless belt thus produced.

From the above description it is seen that 60 applicant has provided a very simple and efficient sorting belt. The belt can be easily quickly and inexpensively made and is easily assembled for initial use and any portions can be readily inserted for repair. The belt is quite flexible and is very durable. The

same has been amply demonstrated in actual practice and is being commercially made.

It will, of course, be understood that various changes may be made in the form, details, proportions and arrangement of the parts 70 without departing from the scope of applicant's invention, which, generally stated, consists in a device capable of carrying out the objects above set forth, in the novel parts and combinations of parts disclosed and defined in the appended claim.

What is claimed is:—

A sorting belt comprising a series of elongated wire members each bent to zigzag form, said members being inter-twined and hinged together to form a continuous belt with polygonal shaped openings therein arranged in staggered relation, said members extending transversely of the belt, the end portions of pairs of said members being bent toward each other and extending longitudinally of the belt with the corresponding extremities pivotally connected together by inter-engaging integrally formed eyes and forming unbroken longitudinal edges for the belt which extend substantially in straight lines.

In testimony whereof I affix my signature.

MARTIN A. PAULSON.
